UNITED STATES PATENT OFFICE.

WILLIAM A. PARDOE, OF SPRINGFIELD, MASSACHUSETTS, ASSIGNOR TO BIGELOW
CARPET COMPANY, A CORPORATION OF MASSACHUSETTS.

DESIGN FOR A RUG.

43,363.

Specification for Design.

Patented Dec. 24, 1912.

Application filed November 21, 1912. Serial No. 732,776. Term of patent 3½ years.

To all whom it may concern:

Be it known that I, WILLIAM A. PARDOE, a citizen of the United States, residing at Springfield, in the county of Hampden and State of Massachusetts, have invented a new, original, and ornamental Design for a Rug, of which the following is a specification, reference being had to the accompanying drawing, forming part thereof.

The drawing illustrates one quarter of a rug showing my new design, the remaining three quarters being duplicates thereof.

I claim:

The ornamental design for a rug, as shown.

WILLIAM A. PARDOE.

Witnesses:

FREDERICK H. STEBBINS,
EDMUND PFLEIDERER.
